UNITED STATES PATENT OFFICE.

WILHELM EGADIUES HANSON, OF LAJORD, SASKATCHEWAN, CANADA.

BARREL HOIST.

Application filed July 29, 1922. Serial No. 578,492.

To all whom it may concern:

Be it known that I, WILHELM EGADIUES HANSON, of the town of Lajord, in the Province of Saskatchewan, Canada, have 5 invented certain new and useful Improvements in Barrel Hoists, of which the following is the specification.

The invention relates to improvements in barrel hoists and an object of the invention 10 is to provide a device which will support a barrel or such like in an inclined or pouring position and which can be adjusted either up or down through varying heights and without having to remove the barrel whilst

15 the adjustment is being made, and further, to arrange the construction thereof such that the appliance automatically locks to support the barrel in any adjusted position.

A further object of the invention is to 20 construct the appliance in a simple, cheap and durable manner and so that the parts can be readily assembled.

A further object of the invention is to construct the appliance so that the adjustment 25 can be made up or down by the simple expedient of rocking the barrel or the rack provided for carrying the barrel.

With the above more important objects in view the invention consists essentially in 30 the arrangement and construction of parts hereinafter more particularly described and later pointed out in the appended claims, reference being had to the accompanying drawing in which:

35 Fig. 1 is a side view of the barrel hoist with the barrel thereon.

Fig. 2 is a front view.

Fig. 3 is an enlarged detailed interior face view of a portion of one of the racks and 40 the parts associated therewith.

Fig. 4 is a perspective view of the parts appearing in Fig. 3.

Fig. 5 is a view similar to Fig. 3 but with the dogs in a different position.

45 Fig. 6 is a reverse view of the parts shown in Fig. 5.

Fig. 7 is a view of parts shown in Fig. 6 but with the dogs in a different position.

Fig. 8 is a reverse view of the parts shown 50 in Fig. 7.

In the drawings like characters of reference indicate corresponding parts in the several figures.

Referring now to the drawings it will be 55 observed that the body or frame of the appliance comprises a stand or base plate 1,

which is provided with two upstanding stationary spaced rack bars 2 and 3, the rack bars having the opposite edges thereof fitted with sets of ratchet teeth 4, the teeth at the one side of each bar being alternated with those at the other side or in zig-zag formation. The height of these rack bars will be such so that a barrel can be raised, as later explained, to a position for conveniently loading onto a wagon and the distance between the rack bars is such that a barrel, indicated at 5, can be readily inserted therebetween.

Between the rack bars I locate a barrel 70 carrier or cradle 6 comprising side beams 7 and 8 and front and rear cross rods 9 and 10 connecting the beams. Centrally the rods are bowed downwardly so as to form a convenient rest for the ends of the barrel. 75 The side beams are fitted centrally each with a pair of spring pressed dogs and a combination dog locking and trip mechanism. The dogs and parts associated therewith are identical at each side so that the description 80 of one pair of dogs and mechanism for controlling the same will suffice.

The racks cross the beams more or less centrally of their length and at the opposite sides of the rack, in each instance, I locate two pivot pins 11 and 12, these pins being carried by the adjoining beam and having their outer ends connected together by a tie strap 13 which passes to the outer side of the rack bar. On the pins I mount a 90 pair of dogs 14 and 15, the dogs being provided with teeth 16 and 17, adapted to engage the teeth of the rack bars and being provided further with upwardly extending and outwardly inclining heads 18 and 19. 95

The heads of the dogs carry inwardly extending pivot pins 20 and 21 and on the inner ends of the pivot pins I mount, pivotally, legs 22 and 23, the upper ends of the legs being provided with catches 24 and 25. 100 A coil spring 26 has the ends thereof caught on the catches and said spring acts to draw the head of the dogs continuously towards the rack bars. The leg 22 is slotted as indicated at 27 and the leg 23 passes through 105 the slot and is adapted to operate therein.

It will be observed that the legs lie more or less closed. The lower ends of the legs are adapted to operate on a wearing plate 28, permanently secured to the top side of the beam and obviously the action of the spring is to hold the lower ends of the legs 110

riding the plate. Centrally, the plate is provided with notches 29, adapted to alternately catch the lower ends of the legs upon the cradle being rocked, as later more fully explained.

On account of the ratchet teeth of the rack bars being alternated it will be seen that the dogs will support the cradle in a normal inclined position. This is desirable 10 as the contents of the barrel will run out freely by gravity, if provided at the bottom with a tap 30 or such like. The arrangement of the dogs and associated parts is such that the barrel can be raised or lowered 15 as wished by rocking or oscillating the barrel with the cradle. This action is now described, assuming the parts initially in the position as best shown in Fig. 1.

Upon the upper or elevated or left hand 20 end of the barrel being pressed down, the dogs 15 become anchored on the engaged teeth of the rack bars and support the weight of the barrel, whilst the dogs 14 escape upwardly over the teeth of the rack bars with 25 which they are engaged and become caught in the next notches higher up. Care is exercised that the left hand end of the barrel, at this time, be not pressed down too far, but simply far enough to permit the right 30 hand dogs to escape into the next notches higher up. Then upon the right hand end of the barrel, which is at this time elevated, being pressed down, the cradle will be rocked in the opposite direction. The dogs 35 14 will then remain caught and the dogs 15 will then escape into the next notches higher up, it being borne in mind also that the barrel be rocked an amount sufficient to permit the dogs simply to catch in the notches 40 higher up.

Accordingly by alternately rocking the ends of the barrel and through the barrel the ends of the cradle, the cradle will gradually move up rack tooth by rack tooth 45 until it is brought to the position desired, where it will remain. This is convenient as one can raise the barrel to drain it into receptacles of varying heights, or he can raise it well up to load it say into a wagon. 50 Further, the rack and consequently the barrel become suspended in all cases in an inclined position so that one can pour from either end of the barrel if needs be.

In the limited, so to speak, rocking movement given the barrel in the aforesaid description, the legs are simply moving idly 55 backwardly and forwardly on the plates but do not become caught in the notches 29.

Referring now to Fig. 1 it will be observed that if the right hand end of the barrel were pressed downwardly further than the position shown in Fig. 1, such would result in the out swinging of the dogs 15, such being brought about by the inclined 60 faces of the engaged teeth of the rack bars.

This further outward movement of the said dogs 15 results in the back pulling of the legs carried by those dogs, the back pulling being to such an amount that the lower ends of the legs are permitted to enter and catch 70 in the notches 29. As soon as the said legs become caught in the notches the dogs 15 are locked, in which position they are shown in Figures 5 and 6. Upon the left hand end of the barrel being then swung downwardly 75 the dogs 14 will anchor the barrel in respect to the racks and the locked dogs 15 will swing out, clear of and downwardly past the then underlying rack teeth and will reach a position as shown in Figures 7 and 8. 80 After they have reached this position and the left hand end of the barrel is swung downwardly further, the lower ends of the legs of the dogs 14 act to trip the legs of the dogs 15 so that they are freed from 85 the notches. Immediately this occurs the dogs 15 swing in under the action of the spring and become caught in the next lower rack tooth.

This being accomplished one can force 90 the left hand end of the barrel still further down and at this time the dogs 15 serve to anchor and support the barrel, whilst the dogs 14 are forced out to an extreme position and locked by the legs associated 95 therewith being caught in the notches 29. The right hand end of the barrel is then rocked downwardly and the dogs 14 are retained locked until they have been swung 100 downwardly clear of the previously engaged rack teeth, at which time the legs of the dogs 14 are tripped by the legs of the dogs 15 and freed from the notches. This results in the dogs 14 escaping into the next rack tooth lower down.

Accordingly by giving the barrel and through the barrel the cradle an increased dip or down push I can cause the dogs to climb down the racks. The mechanism accomplishing this is extremely simple and 110 positive and the operator, by gauging the tilting movement of the barrel, can raise it or lower it as he desires and without having to set any parts by hand or otherwise, the whole action being entirely automatic. 115

What I claim as my invention is:

1. In a hoist, a pair of opposed spaced upright stationary rack bars having similar rack teeth located at the sides thereof, a carrier interposed between the bars, pairs of dogs supporting the carrier from the teeth of the rack bars, and a control mechanism associated with the dogs and carrier causing the dogs to climb or descend the rack bars, dependent upon the amount of up and down swing given the ends of the carrier. 120
2. In a hoist, a pair of similar opposing spaced upright stationary rack bars having ratchet teeth formed on the opposite edges thereof, a cradle interposed between the 125

- rack bars, pairs of spring pressed dogs pivotally attached to the sides of the cradle and engaging the teeth of the rack bars and supporting the cradle from the rack bars, said dogs being designed to alternately climb the rack bars upon the cradle being rocked a predetermined amount, and a combination dog locking and trip mechanism associated with the dogs and cradle and adapted to alternately lock and release the dogs of the pairs and in so doing causing the dogs to descend the rack bars in an abnormal rocking of the cradle.
3. In a hoist, a pair of similar opposed spaced upright rack bars having ratchet teeth formed on the opposite sides thereof and with the ratchet teeth at the opposite sides of the pairs alternating in position, a cradle interposed between the rack bars, pairs of spring pressed dogs pivotally attached centrally to the sides of the cradle and adapted to engage and cooperate with said teeth in supporting the cradle at an inclination with respect to said bars, and a combination dog locking and trip mechanism associated with the dogs and actuated by the rocking of the cradle a predetermined amount and adapted upon the cradle being rocked a predetermined amount to alternately lock and release the dogs and effect the descent of the dogs in respect to the rack bars and the consequent lowering of the cradle.
4. In a hoist, a pair of similar opposed spaced upright rack bars having ratchet teeth formed on the opposite sides thereof and with the ratchet teeth at opposite sides of the bars alternating in position, a cradle interposed between the rack bars, a pair of dogs pivoted to each side of the cradle at a central point adapted to engage and cooperate with said teeth in supporting the cradle in an inclined position with respect to said bars, trip legs pivotally connected to the dogs and having their lower ends riding the upper edges of the cradle sides,
- springs connecting the upper ends of the legs and normally pressing the pairs of dogs toward the rack bars and the lower ends of the legs against the cradle, and means for alternately locking and releasing the lower ends of the legs to alternately lock and release the dogs and effect the descent of the dogs on the rack bars upon the cradle being abnormally rocked.
5. In a hoist, a pair of similar opposed spaced upright rack bars having ratchet teeth formed on the opposite sides thereof and with the ratchet teeth at opposite sides of the bars alternating in position, a cradle interposed between the rack bars, pairs of dogs pivotally attached centrally to the sides of the cradle and engaging the teeth of the rack bars to support the cradle at an inclination with respect to said bars, pairs of trip legs pivotally secured to the pairs of dogs, one of the trip legs of each pair being slotted to receive the other leg of the pair, plates secured to the upper faces of the sides of the cradle, said plates being each provided with a central notch adapted to receive and alternately lock the lower ends of the legs, said pairs of legs being further designed to alternately release one another from the notches in the rocking movement of the cradle, springs connecting the upper ends of the legs and holding the lower ends thereof riding the plates and also pressing the pairs of dogs toward the rack bars.
6. The combination of a supporting structure, an oscillatory load carrier movable vertically with respect thereto, and means for causing the load carrier to ascend or descend the supporting structure dependent upon the extent to which the load carrier is oscillated.

Signed at Winnipeg, this 22nd day of May 1922.

WILHELM EGADIUS HANSON.
